UNITED STATES PATENT OFFICE.

OLE NIELSEN, OF THORNTON, IOWA.

ROOF SCAFFOLDING-BRACKET.

1,148,919.

Specification of Letters Patent.

Patented Aug. 3, 1915.

Application filed September 25, 1914. Serial No. 863,461.

To all whom it may concern:

Be it known that I, OLE NIELSEN, citizen of the United States, residing at Thornton, in the county of Cerro Gordo and State of Iowa, have invented certain new and useful Improvements in Roof Scaffolding-Brackets; and I do hereby declare the following to be a full, clear, and exact description of the invention, such as will enable others skilled in the art to which it appertains to make and use the same.

My invention has for its object to provide an improved roof scaffolding bracket, intended for general use, but especially adapted for bricklayers in building and repairing chimneys.

To the above end, generally stated, the invention consists of the novel construction and arrangement of parts hereinafter described and defined in the claim.

In the accompanying drawings, which illustrate the invention, like characters indicate like parts throughout the several views.

Referring to the drawings, Figure 1 is an end elevation of a gable roof with a chimney projecting therethrough, having a work platform supported on two sides of said chimney by a pair of the improved scaffolding brackets; Fig. 2 is a side elevation of the same; Fig. 3 is a side elevation of one of the improved scaffolding brackets, on an enlarged scale; Fig. 4 is a plan view of the brackets shown in Fig. 3; and Fig. 5 is a side elevation of one of the improved scaffolding brackets, folded.

The numeral 1 indicates a gable roof and the numeral 2 indicates a chimney projecting therethrough. A pair of the improved scaffolding brackets straddle the roof 1, on opposite sides of the chimney 2, and support a work platform 3, comprising a multiplicity of boards, separated to permit said chimney to project therethrough. These brackets are identical, one with the other, and the detailed description of the one will suffice for the other.

Each scaffolding bracket comprises a horizontal platform-supporting beam, a pair of diverging legs 5 and struts 6. The beam 4 extends transversely of the ridge piece and is provided at its longitudinal center with a V-shaped notch 7. This notch 7 is cut in the under edge of the beam 4 to receive the apex of the ridge piece on which

the said beam directly rests. Bolts 8 pivotally connect the upper ends of the legs 5 to the intermediate portion of the beam 4, one on each side of the notch 7. Transversely extended roof-engaging feet 9 are secured to the lower or free ends of the legs 5. The legs 5 straddle the roof 1 and the outer ends of the beam 4 are supported therefrom by the struts 6. Formed in the lower end portions of the upper longitudinal edges of the legs 5 are semicircular seats 10 in which are seated the semicircular lower ends of the struts 6. Short links 11, each comprising a pair of laterally spaced metallic straps, pivotally connect the lower ends of the struts 6 to the legs 5 with freedom for angular adjustment toward and from said legs and for folding movement into engagement therewith. To permit the legs 5 to be adjusted so as to fit roofs of different pitch, the upper ends of the struts 6 are adjustably connected to the beam 4 by bolts 12. These bolts 12 are seated in the outer end portions of the beam 4 and are adapted to be inserted through any one of 80 a multiplicity of longitudinally spaced perforations 13, formed in the upper end portions of said struts. Each bolt 12 is provided with a hand-piece equipped nut 14 for holding the same in position.

When the scaffolding brackets are not in use, the beam, legs and struts are folded into parallel arrangement, as shown in Fig. 5. In this position of the parts, the bolts 12 are passed through the struts 6 and through 90 perforated ears 15 on the beam 4, to lock the parts in their folded position.

From the foregoing description it is evident that each scaffolding bracket is self-supporting on the roof, thus avoiding the use of nails, objectionable on account of the resulting mutilation and leakage of the roof. The bracket can be readily adjusted to fit roofs of different pitch without the use of tools, and, when not in use, may be 100 folded into compact form to facilitate the storing or moving of the same.

The above described device, while extremely simple and of comparatively small cost to manufacture, has in actual usage 105 proven highly efficient for the purpose had in view.

What I claim is:—

A self-supporting roof scaffolding bracket, comprising a platform-supporting 110

beam, a pair of diverging legs pivoted to the intermediate portion of said beam and having roof-engaging feet, struts having one of their ends removably mounted in seats in the free end portions of said legs, links pivotally connecting said struts to said legs with freedom for angular adjustment with respect thereto and for folding movement out of said seats into flat en-

gagement therewith, and means for adjustably connecting said struts to said beam.

In testimony whereof I affix my signature in presence of two witnesses.

OLE NIELSEN.

Witnesses:

O. P. JACOBSEN,
L. N. BECK.
